CLAIM

The ornamental design for a “lighting fixture end cap,” as shown and described.

DESCRIPTION

This application may be deemed related to commonly owned copending U.S. Design patent application Ser. No. 29/272, 879 entitled “Fixture Base for LED Strip” filed even date herewith, which application is expressly incorporated hereinto by reference.

FIG. 1 is a front perspective view of one embodiment of a lighting fixture end cap which embodies my new and original design therefore and which is especially adapted for use as a left end cap of a lighting fixture base;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is front perspective view thereof similar to FIG. 1 but showing in broken line certain environmental structural components;

FIG. 9 is a front perspective view of another embodiment of a lighting fixture end cap which embodies my new and original design therefore and which is especially adapted for use as a right end cap of a lighting fixture base;

FIG. 10 is a front elevation view thereof;

FIG. 11 is a rear elevation view thereof;

FIG. 12 is a top plan view thereof;

FIG. 13 is a bottom plan view thereof;

FIG. 14 is a left side elevation view thereof;

FIG. 15 is a right side elevation view thereof; and,

FIG. 16 is a front perspective view thereof similar to FIG. 9 but showing in broken lines certain environmental structural components.

The broken lines in FIGS. 8 and 16 represent a lighting fixture base and a light emitting diode (LED) lighting strip which may be in the environment of the claimed designs, but which do not form part of the claimed design.
